US00D967822S

(12) **United States Design Patent** (10) **Patent No.:** **US D967,822 S**
(45) **Date of Patent:** **** Oct. 25, 2022**

(54) **COMPUTER INPUT DEVICE**

(71) Applicant: **ACCO Brands Corporation**, Lake Zurich, IL (US)

(72) Inventors: **Erik Campbell**, San Francisco, CA (US); **Abraham Camacho**, Phoenix, AZ (US); **Anita Chang**, Taipei (TW)

(73) Assignee: **ACCO Brands Corporation**, Lake Zurich, IL (US)

(**) Term: **15 Years**

(21) Appl. No.: **29/831,666**

(22) Filed: **Mar. 22, 2022**

Related U.S. Application Data

(62) Division of application No. 29/733,783, filed on May 6, 2020, now Pat. No. Des. 950,552.

CLAIM

We claim the ornamental design for a computer input device, as shown and described.

DESCRIPTION

FIG. 1 is a perspective view of a computer input device. FIG. 2 is a first side view of the computer input device shown in FIG. 1.

FIG. 3 is a second side view of the computer input device shown in FIG. 1.

FIG. 4 is a front view of the computer input device shown in FIG. 1.

FIG. 5 is a rear view of the computer input device shown in FIG. 1.

FIG. 6 is a top view of the computer input device shown in FIG. 1; and,

FIG. 7 is a bottom view of the computer input device shown in FIG. 1.

The broken lines having equal segments represent portions of the article that form no part of the claimed design.

1 Claim, 6 Drawing Sheets
